AUTOMATIC STOKER

James E. Imrie and William Walter Hudson,
Salt Lake City, Utah

Application April 22, 1931, Serial No. 532,054

1 Claim. (Cl. 110—45)

The present invention relates to improvements in automatic stokers, and more particularly relates to air and coal supply equipment for automatic coal burner stokers.

5 In stokers of the above description trouble is often experienced in securing even or symmetrical distribution of the combustion air to all parts of the fire through the several openings provided for that purpose in the firepot or tuyère block 10 within the furnace.

This difficulty is in great part due to the prevalent custom of connecting the air-supply pipe from the fan to a point at one side or the other of the tuyère block instead of centrally as is 15 usually the case with the coal-supply pipe. This arrangement naturally tends to cause most of the air supplied to pass through the openings or tuyères on that side of the tuyère block at which it is introduced from the air-supply pipe, and to 20 "starve" those on the opposite side; thus causing an over-supply of air to one side of the fire and inadequate supply to the other side. This results in seriously interfering with the efficient operation of the furnace.

25 An object and purpose of the invention is to arrange for the introduction of the air to the tuyère block in such a manner as to overcome the foregoing difficulties and to facilitate the symmetrical distribution of the air to both sides of 30 the fire.

A further object of the invention is to provide a device in which the air is introduced in such manner that it will have a cooling effect upon the conveyor, coal-supply pipe and coal content 35 of same, thus preventing over-heating taking place and avoiding possible damage to the screw conveyor and the coal-supply pipe.

Additional objects of the invention are to provide a blower and air-pipe assembly that will be 40 unusually neat and compact, and to so locate the blower, etc., that the air-pipe to the tuyère block will be as short and straight as possible.

With the foregoing and other objects in view, the invention will be more fully described hereinafter, and will be more particularly pointed out in the claims appended hereto.

In the drawings, wherein like symbols refer to the same or corresponding parts throughout the several views:

50 Figure 1 is a side elevation, with parts broken away and parts shown in section, of an improved furnace and automatic stoker constructed in accordance with the present invention.

Figure 2 is a horizontal section taken on the 55 line 2—2 in Figure 1 with parts broken away,

Figure 3 is a fragmentary plan view, on an enlarged scale of the tuyère block and pipe connections.

Figure 4 is a vertical longitudinal section taken on the line 4—4 in Figure 3.

Figure 5 is a horizontal longitudinal section taken on the line 5—5 in Figure 4.

Figure 6 is a horizontal section taken on the line 6—6 in Figure 4.

Figure 7 is a similar view taken on the line 7—7 in Figure 4, and

Figure 8 is a cross section taken on the line 8—8 also in Figure 4.

Referring more particularly to the drawings 15 designates a hot-air furnace constructed in any conventional manner. The hot air furnace has been selected for illustration as being the most convenient type to show on the drawings, but the invention is, of course, equally applicable to other types of furnaces, such as steam and hot water, 20 and those for special industrial applications.

With the furnace 10 is associated an automatic stoker consisting of the coal hopper 11, coal-supply pipe 12 and air-supply pipe 13 connecting with the base member 14 of the retort structure 25 comprising said member and an annular tuyère block 19 mounted thereon. The base member 14 includes an inner fuel passage or compartment 21 communicating with fuel pipe 12, and an outer air chamber or jacket 22 surrounding said passage and communicating with air pipe 13 and with the tuyère block. This pipe 13 may be secured to the block 14 in any desired manner, as by a pressed fit, threads, or the like. Coal is conveyed from the hopper through the pipe 12 by 30 means of the screw conveyor 15, which may be driven by the electric or other motor 16 through a suitable mechanical train 17. Air is forced through pipe 13 to tuyère block 14 by a fan or 35 blower 18, which may be driven by the same motor 16.

The air-supply pipe 13 is in the form of a jacket completely enclosing the coal-supply pipe 12 along substantially its entire length from the point where it leaves the coal hopper 11 to the point where it enters the base member 14. It will be evident that the two pipes 12 and 13 enter the base member 14 at such point and in such a direction that the coal entering the inner compartment 21 of the base member and the air entering the air jacket 22, are in each case evenly and symmetrically distributed; the coal being evenly spread and propelled up through the inner compartment 21; and the air propelled with equal force and in equal volume around through both 40

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

sides of air jacket 22 so that there is no tendency for either coal or air to accumulate more at any one point than at any other. The coal, therefore, forms a symmetrical pile or bed in the inner compartment 21 and flows evenly over all sides of the same into the body of the fire in the furnace as indicated in Figure 1. The air passes up and around through the air jacket 22 and enters the fuel bed symmetrically from all directions through apertures or tuyères 23.

It will also be seen from the drawings that the air-supply pipe 13, on account of its shape and location surrounding the coal supply pipe 12 provides a continuous flow of air from the fan or blower 18, in the form of an annular blanket surrounding pipe 12 for substantially its entire length, thus causing a cooling effect on coal-supply pipe 12 and screw conveyor 15, and preventing them from becoming over-heated, with undesirable and possibly dangerous results.

It will also be seen that the location of the fan 18 renders possible the use of an unusually short air-supply pipe 13 and one free from an excessive number of bends, this pipe being unvaryingly straight from the point of introduction of the air from the fan 18 to the point where the pipe enters the base member 14. There is also compactness and general desirability about the arrangement shown.

It will thus be evident that all of the purposes of the invention are fulfilled, namely: the invention provides means for the even and symmetrical distribution of the combustion air in the improved tuyère block; it also provides a cooling film of air surrounding the coal-supply pipe 12, thus preventing the over-heating of the same and of the screw conveyor and coal being conveyed; and it provides a short, straight air-supply pipe 13 from the fan to the tuyère block, together with a generally neat and compact arrangement of the device as a whole.

In Figure 8 the two parts of the retort structure are shown as connected together by lugs 24 and bolts or other fastenings 25; although the securing of these parts together might be ac-

complished in any manner where it is desirable to manufacture the same separately.

The upper portion of the base member 14 is, of course, open upwardly not only as regards the inner chamber 21 but also with respect to the air jacket 22. Connecting webs 26 may be arranged between the outer walls of the jacket 22 and the walls of the inner coal chamber 21. The pipes 12 and 13 may be connected with the base member in any appropriate manner.

In Figure 5 we have shown the air-pipe 13 as fitting within a flange 27 of the base member and against a shoulder 28 thereof; while the inner coal-supply pipe 12 is disposed within an inner flange 29 and against a shoulder 30 of the base member, the pipe being held in place by bolts 31 which screw into the base member and engage lugs 32 of the pipe 12.

It is obvious that various changes and modifications may be made in the details of construction and design of the above specifically described embodiment of this invention without departing from the spirit thereof, such changes and modifications being restricted only by the scope of the following claim.

What is claimed is:—

In an automatic stoker for furnaces, a retort structure comprising a base member and tuyère block disposed in the furnace, said base member and said block each having an inner fuel compartment and an outer air jacket surrounding the same, said air jacket and fuel compartment of the base member being provided with cylindric coaxial intake flanges, a fuel pipe having its end inserted in the intake flange of the fuel compartment, outstanding lugs carried by said fuel pipe, spacing members engaging the fuel compartment and the air jacket of the base member, securing means engaging said lugs and said spacing members for detachably securing said fuel pipe to the base member, and an air pipe having its end inserted in the flange of the air jacket.

JAMES E. IMRIE.

WILLIAM WALTER HUDSON.
